AUTOMOBILE HEATER

Phelps M. Freer, Detroit, Mich.

Application October 27, 1949, Serial No. 123,841

6 Claims. (Cl. 257—137)

1

This invention relates to heat exchange devices and, in particular, to heaters of the type that may be used in automobiles and the like.

It is an object of the invention to increase the heat transfer efficiency of heaters of the type described and thus reduce the size-capacity ratio and the cost of the heater unit.

Another object is to provide a heater that may be economically made from sheet metal parts.

These and other objects of the invention are accomplished by means of a heater construction in which the conduit or coil for the fluid heating medium is of sinuous shape and preferably made from originally flat, spaced, superposed sheets of metal secured together at their side edges. The sinuous coil is placed in a sheet metal box that has bulges in the sides upon which the curved portions of the coil rest whereby the coil is fitted into and supported by the sides of the box. A cover is yieldably attached to the box to close the opening through which the coil is inserted and serves as a side thereof. Each of the sides of the box which is normal to the sides that support the coil is formed with bulges that are staggered with respect to the bulges in the opposite side and serve to direct air back and forth in sinuous passage from one loop to another of the coil. The coil is formed with projections and fins that serve to create turbulent air flow and this may be further promoted by the use of irregularly surfaced divider plates between adjacent sections of the coil. The core formed by the box and coil may be encased at opposite walls by inlet and outlet manifolds and, if desired, a flow impeller may be secured to one of the manifolds to form a self-contained heater unit.

By virtue of the foregoing construction, the heater is endowed with an extremely large area of heat-conducting contact between air and coil. The use of fins on the coil serves also to transfer heat to the air by radiation. The turbulence provoking projections and the fins tend to cause air flow that removes the boundary layer and the divider plate tends to prevent stratification, thus providing optimum conditions for the transfer of heat from the heating liquid to the air. The turbulence projections also increase the surface area of the coil and serve to create some turbulence in the heating liquid flowing therein. The net result of these and other features is to provide a high rate of heat transfer in a small-size unit.

Other objects and features of the invention will become apparent upon consideration of the accompanying drawings, in which:

Figure 1 is a side elevation of the heater attached to the firewall of an automobile;

Fig. 2 is a side elevation, partly broken away, of the improved heater;

Fig. 3 is an elevation taken from the right of Fig. 2, with parts broken away;

2

Fig. 4 is a section taken on line 4—4 of Fig. 2;

Fig. 5 is an enlarged view of the structure contained with the circle 5 of Fig. 2; and

Fig. 6 is a sectional view of a plug valve that may be used in forming the sinuous coil of the invention.

The automobile heater of this invention has a sinuous thin-walled heat exchange coil 1 for the passage of heating liquid from the radiator. It comprises a plurality of straight sections 3 (Fig. 4), each of which is joined at its ends to an adjacent straight section by a recurved section 5. The internal sinuous passage for fluid is designated by the reference numeral 7. This coil is designed to give a high ratio of surface area to volume and therefore its width and its loop length (distance between oppositely disposed recurvatures 5) are substantially larger than its thickness. While the coil surfaces are illustrated as flat, they may be undulated or corrugated to increase the surface area and desirably affect fluid flow. The coil is made of suitable corrosion-resistant material, copper being the conventional material for this purpose. The coil may be formed from different types of raw stock, and it is not intended to limit the invention, in its broad aspects, to the history of manufacture of the coil. For example, the coil may be bent from tubing that is originally formed to the desired cross-sectional shape. Again, it may be formed by flattening round tubing and then bending the product into sinuous shape. Advantage is more readily taken of certain detail features of the invention, however, when the coil is formed from originally flat sheet metal. It is possible to make the coil tube from sheet metal in either of two ways, the second of which is preferred and illustrated herein, viz. (1) by forming and folding a single sheet of metal and then securing its edges together (as by soldering or the like) to give the desired cross section, and (2) by forming two separate sheets of metal and then soldering or otherwise securing their flanged edges together with the surfaces of the sheets in spaced superposition, as best indicated in Fig. 5. It will be recognized that generically the coil formed by either of these two methods may be described as one comprised of a pair of spaced superposed sheets having their side edges sealingly interconnected or secured together.

The opposite faces or pieces 11 of the coil each have a multiplicity of outwardly extending projections or bosses 13 pressed therein which are generally round in cross section. They serve to create turbulence in the air flowing by and thus to cause some scrubbing of the boundary layer, and also increase the surface area and cause turbulence in the heating fluid flowing through the coil. The coil pieces 11 also have generally round inward projections 15 that serve to maintain the

proper spacing between the pieces and which may thus engage similar projections on opposite coil pieces, as illustrated, or be of a length equal to the width of the passage so as to engage the flat face of the opposite piece. The projections 15 are sufficiently few in number so that they do not appreciably interfere with the flow of water through the passage 7, though it is desirable that they create some turbulence in liquid flowing through the coil. The upper open end of the coil 1 (Fig. 4) forms the outlet for water and is adapted to discharge it into a suitable hose by a length of pipe or tubing 17 that has a slot 19 therein registering with the end opening of the coil. The ends of the pieces 11 may be flanged at 21 and soldered to the surface of the tubing 17, as indicated, to effectuate the desired watertight connection. The lower open end of the coil 1 forms the inlet for water from the radiator and is provided in a similar manner with a pipe or tube 23.

The coil 1 may be manufactured by several methods, features of which obviously may be used in constructing the coil from various of the types of raw stock mentioned above. In one method straight dished pieces 11 with the projections formed therein of the developed length of the coil are separately bent into sinuous form, placed together, and the edges clamped and soldered. In another method, straight pieces of the developed length are joined together by soldering of the flanges 9 after the projections 13 and 15 have been formed therein but prior to bending into sinuous shape. The outlet and inlet tubes 17 and 23 are preferably attached to the ends before bending. The sections of the pieces 11 which are to form the outside of the curved sections 5 are desirably provided before soldering with outwardly pressed arcuate ribs 25 (Fig. 4) that extend the full width of the coil. The diameters or chords of these ribs expand during bending of the pieces into the curved sections 5 to prevent flattening at those sections. As a further precaution against flattening and undesired restriction of passage 7, the straight flat tube is preferably filled with water (or other substantially incompressible liquid) prior to bending into the sinuous form. This may be done by plugging both of the pipes 17 and 23. It is desirable that at least one of these plugs be in the form of a pressure relief cap 27, such as shown in Fig. 6. The cap 27 comprises a plug body 29 that is adapted to sealingly fit in the end of a pipe, as pipe 17. The body has an aperture 31 which is enlarged to form a valve seat 33 and a spring chamber 35. The body is threaded to receive an apertured retainer 37 to bear upon a spring 39 that holds the ball 41 on the seat 33 with a desired and adjustable force. It is obvious that if at any time during the bending of the flat soldered pieces 11 excessive diminution of volume of the passage 7 takes place, the ball 41 will be forced off its seat to relieve pressure in the passage and indicate that the bending process is proceeding in an improper manner. Before this takes place, however, the liquid in the coil, being substantially incompressible, will serve to prevent restriction of the passage 7.

Instead of forming the coil 1 by bending continuous developed lengths of the pieces 11, a build-up procedure may be employed. In this method flat sections of a length that accommodates less than all of the curved sections 5 are bent and then joined with other sections to form the complete coil. For example, the coil may be

built up from U-shaped sections that are provided at their ends with flanges, as indicated at 43 in Fig. 3. The flanges of enough sections are then soldered together to form the sinuous coil 1. In this method the spaced superposed sheets may be soldered together first and then bent, or bent first and then soldered together.

The coil 1 fits in a sheet metal box 45 and these two elements form the heater core. The box 45 has five integral sides and the sixth and open side is closed by a cover 47 that has a flange that fits inside the box, as indicated at 49. The side walls 51 and 53 of the box that define the open side of the box have bulges or curved sections 55 therein that correspond to the curved sections 5 of the coil 1. They, and also the top and bottom 57 and 59 of the box, also have cylindrical enlargements 61 to receive the pipes 17 and 23 on the coil 1. If the cover 47 is removed from the box 45, the coil 1 can then be slipped into it, and the curved sections 5 fit in and on the bulges 55 which therefore serve to support the coil. The curved sections 55 may have inwardly pressed projections 63 therein to engage the coil 1 and facilitate this assembly.

Air is allowed to flow in a sinuous path through the coil 1 by outwardly curved sections 65 and 66 that are formed in the front wall 67 of the box and in the cover 47 that forms the rear wall of the box. The curved sections 65 and 66 are adjacent the side flanges 9 of the coil and alternately place opposite sides of the straight coil sections 3 in communication with each other.

Air enters the core through an inlet 69 that is formed in the cover 47 and extends the width thereof and which registers with the air passage between the top two straight sections 3 of the coil. A similar opening 71 in the front wall 67 adjacent the air passage between the bottom two straight sections 3 of the coil forms the outlet for air. Between the inlet and outlet, the air flows downwardly back and forth between the straight sections 3 of the coil 1 and between the curved front wall sections 65 and the curved rear cover sections 66. In the meantime, water or other heat-supplying medium flows upwardly from inlet pipe 23 in the coil passage 7 back and forth between the sides 51 and 53 of the core to the outlet pipe 17.

The cover 47 has suitable apertures for the passage of pipes 17 and 23. It is yieldably held in place on the box 45 by several pins 72 that extend through the box and may shoulder on the outside of the front wall 67 and have a weak coil spring 73 thereon that is pressed against the outside of the cover 47 by insertion of a cotter pin 74 through a suitable aperture in the pin. Inward movement of the cover 47 is prevented by the coil flanges 9. Alternate straight sections 3 that are staggered in opposite sides of the coil have the flanges 9 squared off or cut off on a straight edge. These straight edges bear against flat surfaces on the front wall 67 and cover 47 between the curved sections 65 and 66 to determine the minimum overall front-to-rear dimension of the core which is yieldably maintained by the springs 73.

The front and rear of the core are enclosed by headers or manifolds 75 and 77, respectively. These, like the box 45 and cover 47, are preferably pressed from sheet steel and are adapted to receive the pipes 17 and 23. They shoulder on the box and cover as indicated at 79 and are generically similar to covers and thus fit snugly on the box. The rear or inlet manifold 77 has a

5

length of arched spring wire 81 secured by a pin or rivet 83 to the inside of its rear wall which bears upon the cover 47 and stresses the parts of the heater so as to prevent relative movement and rattling. When spring 83 is used, the pins 72 and coil springs 73 may be eliminated. The manifolds are forced on their shouldered seats 78 by bolts 85 that extend through the entire assembly of manifolds and core. The rear manifold is apertured at 87 to allow air to flow to the inlet 69. The front manifold has an opening 89 to allow air to flow from the outlet 11.

An impeller may be used to induce air flow through the present heater and may be placed on the inlet side to flow air through, but preferably is placed on the outlet side thereof to establish a negative air pressure which results in more effective air flow by the coil 1. This may be accomplished by providing the outlet manifold 75 with a collar 91 surrounding the opening 89 and suspending therein a suitable flow-inducing fan 93.

It is evident from the structure already described that by providing a counter sinuous flow of air and heating water in conjunction with a flat surfaced sinuous coil a maximum surface for heat conduction is achieved. The efficiency is increased further by providing the flanges 9 of the coil 1 which fit in the curved sections 65 and 66 with fins, as best illustrated in Fig. 5. The fins not only furnish heat by radiation, but also serve to increase the efficiency of heat transfer by conduction by promoting turbulent flow of the air. The fins are illustrated as being formed in two different ways. In one, the double thickness of metal forming the soldered or brazed flange 9 is extended beyond the previously mentioned straight edge flanges and then slit and bent alternately in opposite directions to form the fins 95 that are radial with respect to the curved section 66 but spaced therefrom so as to allow unthrottled passage of air. In the other method, the two thicknesses of metal are separated beyond the soldered flange 9 and each bent on a different angle to form fins 97 that are radial to the curved sections 66.

The fins 95 and 97 and the projections 13 all serve to create turbulent flow of the air passing through the core, and thus insure maximum heating of the air. Turbulence or prevention of lamellar air flow and stratification may be promoted further by the use of flow divider plates 99 that are brazed, welded, or otherwise suitably attached alternately to the side walls 51 and 53 of the box by means of flanges 101 at positions midway between straight sections of the coil 1. The plates have corrugations or ribs 103 transverse to the air flow pressed therein, which extend out opposite sides thereof to provide rigidity and by varying the size of the air passage create an aspirator effect that produces turbulence in the air flowing through the core. It is to be noted that the plates 99 provide these beneficial effects without materially reducing the size of the passage through which the air flows. Obviously, the aspirator effect can also be produced by making the coil surfaces of undulatory form.

The box 45, cover 47, and manifolds 75 and 77 may be employed as a self-contained heater and secured to the fire wall of a vehicle by brackets 110, as illustrated in Fig. 1.

Modifications may obviously be made in the specific structure herein described without departing from the spirit of the invention.

What is claimed is:

6

1. A heat exchanger comprising spaced superposed sheets sealingly secured together at their side edges and of sinuous form providing a sinuous coil for heating fluid, said sheets having outward turbulence-provoking bosses thereon, said sheets having inward bosses thereon, portions of the side edges of said sheets being inclined to the plane of the sheets to form radiation and turbulence-provoking fins, an inlet pipe for the coil communicatively secured to one end of the sheets, an outlet pipe for the coil communicatively secured to the other end of the sheets, a box having outward bulges in a pair of opposite sides that conform to and receive and support the recurvities of the sinuous coil, said box sides having inward projections therein engaging the surface of the coil, said box having an opening in a side normal to the sides which support the sinuous coil whereby the coil may be inserted in the box, a cover for said opening, means yieldably pressing the cover against the secured side edges of the sheets and forcing opposite secured side edges of the sheets against the side of the box opposite the cover, said cover, box and coil defining a core, means providing inlet and outlet openings in the walls of the core, bulges in the cover and the side opposite the cover for directing fluid to be heated from the inlet to the outlet in a sinuous path over the coil back and forth between the cover and the side opposite, flow divider plates having turbulence-provoking ribs thereon located between adjacent sections of the coil, manifold cover means fitting the box over the inlet and outlet openings for the fluid to be heated, spring means associated with the manifold cover means applying yieldable pressure to the cover for the box, said manifold cover means having inlet and outlet openings in communication with the inlet and outlet openings in the core, and impeller means for actuating flow of fluid to be heated, said impeller means being located at the outlet of the core to establish negative pressure in the core, said impeller means being supported upon the manifold cover means.

2. An auto heater comprising a tube having a width substantially greater than its thickness and of sinuous form providing a sinuous coil for heating fluid, a box having outward bulges in a pair of opposite sides that conform to and receive and support the recurvities of the sinuous coil, said box having a removable side normal to the sides which support the sinuous coil whereby the coil may be inserted in the box by movement transverse to the length of the coil passes, means providing inlet and outlet openings in the box, and bulges in the removable side and the side opposite the removable side communicating with the spaces between the coil passes for directing fluid to be heated from the inlet opening to the outlet opening in a sinuous path over the coil back and forth between the removable side and the side opposite.

3. An auto heater comprising a tube having a width substantially greater than its thickness and of sinuous form providing a sinuous coil for heating fluid, a box having outward bulges in a pair of opposite sides that conform to and receive and support the recurvities of the sinuous coil, said box having an opening in a side normal to the sides which support the sinuous coil whereby the coil may be inserted in the box by movement transverse to the length of the coil passes, a cover for said opening and forming a side of the box, means providing inlet and outlet openings in the box, bulges in the cover and the side

opposite the cover communicating with the spaces between the coil passes for directing fluid to be heated from the inlet opening to the outlet opening in a sinuous path over the coil back and forth between the cover and the side opposite, and manifold cover means fitting the box over the inlet and outlet openings for the fluid to be heated.

4. An auto heater comprising a tube having a width substantially greater than its thickness and of sinuous form providing a sinuous coil for heating fluid, a box having outward bulges in a pair of opposite sides that conform to and receive and support the recurvities of the sinuous coil, said box having a removable side normal to the sides which support the sinuous coil whereby the coil may be inserted in the box by movement transverse to the length of the coil passes, means providing inlet and outlet openings in the box, and bulges in the removable side and the side opposite the removable side communicating with the spaces between the coil passes for directing fluid to be heated from the inlet opening to the outlet opening in a sinuous path over the coil back and forth between the removable side and the side opposite, and impeller means for actuating flow of fluid to be heated.

5. An auto heater comprising a tube having a width substantially greater than its thickness and of sinuous form providing a sinuous coil for heating fluid, a box having outward bulges in a pair of opposite sides that conform to and receive and support the recurvities of the sinuous coil, said box having a removable side normal to the sides which support the sinuous coil whereby the coil may be inserted in the box by movement transverse to the length of the coil passes, means providing inlet and outlet openings in the box, bulges in the removable side and the side opposite the removable side communicating with the spaces between the coil passes for directing fluid to be heated from the inlet opening to the outlet opening in a sinuous path over the coil back and forth between the removable side and the side opposite,

and impeller means for actuating flow of fluid to be heated, said impeller means being located at the outlet of the core to establish negative pressure in the core.

6. An auto heater comprising a tube having a width substantially greater than its thickness and of sinuous form providing a sinuous coil for heating fluid, a box having outward bulges in a pair of opposite sides that conform to and receive and support the recurvities of the sinuous coil, said box having a movable side normal to the sides which support the sinuous coil whereby the coil may be inserted in the box, means providing inlet and outlet openings in the box, and bulges in the removable side and the side opposite the removable side communicating with the spaces between the coil passes for directing fluid to be heated from the inlet opening to the outlet opening in a sinuous path over the coil back and forth between the removable side and the side opposite, and resilient means for holding the removable side in place in the box.
